Lacy Tracy, Attorney

UNITED STATES PATENT OFFICE.

WILLIAM H. EBERT AND ALBERT G. EBERT, OF BUFFALO, NEW YORK.

BEVEL.

Application filed December 29, 1924. Serial No. 753,737.

This invention relates to improvements in carpenters' bevels and has as one of its objects to provide an instrument of this class which may be readily adjusted to position its component parts at any desired angle with respect to each other and the instrument then employed in marking lumber such as rafters, sills, beams, etc., preparatory to cutting the same to the required dimensions.

10 Another object of the invention is to provide a carpenter's bevel which may be manufactured at an exceptionally low cost and which will be substantial in its construction and, therefore, not liable to distortion or 15 disarrangement of its component parts.

In the accompanying drawings:

Figure 1 is a view partly in plan and partly in section, illustrating the instrument embodying the invention.

20 Figure 2 is a vertical sectional view taken substantially on the line 2—2 of Figure 1, looking in the direction indicated by the arrows.

The bevel comprises a stock which is indicated by the numeral 1, and which may be made of wood or of metal, either as desired, and this stock is of oblong rectangular form and has parallel side edges indicated by the numeral 2 which are of right line extent and 30 either of which may, therefore, constitute a straight edge. Near one end, the stock is formed with a slot 3 opening through its edges 2 and positioned midway between the planes of the opposite faces of the stock.

35 The blade of the bevel is indicated by the numeral 4 and the same is of metal and has parallel longitudinal straight edges indicated by the numeral 5. If desired, one end of the blade may be cut at an angle as at 6, 40 and the other end of the blade is formed with a slot 7 which extends longitudinally of the blade at the said end thereof and midway between and parallel to the straight edges 5. The walls of the slot 3 are formed 45 with alined openings 8, and the shank of a set bolt 9 is fitted through the openings 8 and through the slot 7, a wing nut 10 being threaded onto the bolt to bear against a washer 11 which is interposed between the 50 said wing nut and one face of the stock 1. The head 12 of the bolt is located at the opposite face of the stock and a washer 13 is interposed between the said head of the bolt and the said face of the stock. Whether 55 the stock be formed of wood or of metal, the

walls of the slot 3 will possess a greater or less degree of resiliency and, therefore, while the slotted end of the blade 4 is both slidably and angularly adjustable within the slot and fits relatively snugly therein, the blade may be secured in any desired position of adjustment contemplated by the invention, by tightening the nut 10 so as to draw the walls of the slot toward each other and thus securely frictionally binding the opposite sides 60 of the blade.

That end edge of the blade 4 which is next adjacent the slot 7, is indicated by the numeral 14 and the same is at right angles to and meets one of the straight edges 5 of the 70 blade. The blade at the other straight edge is provided with an offset or extension 15 so as to afford room for a scale 16, the marks of which are impressed upon one face of the blade at its said end and upon the corresponding face of the extension 15. A similar scale 17 has its marks impressed upon the said face of the blade along the straight edge 5 which meets the edge 14. The scale marks are consecutively numbered, beginning from the corner of the blade formed by the edges 5 and 14, from 0 to 12, and the divisions of each scale are representative of inches and fractions of inches, the actual linear length of each scale being, however, 75 much less, of course, than the linear distance of which it is representative. The lateral extension 15 is pointed to admit of the tool being used in the capacity of the usual scratch gage, the marking point being directed by the stock 1 which functions as a 80 guard.

It is the well known practice of carpenters to make use of an ordinary steel square in cutting lumber such, for example, as rafters, but even when an ordinary square is employed by skilled workmen, errors are liable to be made. By the use of the present invention and by loosening the set nut 10, the user of the instrument may adjust the blade 100 4 so as to bring the proper scale marks of the scales 16 and 17 into registration with the adjacent straight edge 2 of the stock, thereby positioning the projecting length of the blade at the proper angle to the other straight edge of the stock to permit of the use of the instrument in marking the lumber to be cut. Of course, when the set nut 10 is tightened, the blade 4 will be held securely 105 in the position to which it has been adjusted, 110

and the instrument may then be employed by the carpenter in accurately marking the lumber to be cut.

Having thus described the invention, what we claim is:

A tool of the character described comprising a stock having one end portion formed with a slot closed at its ends and opening through opposite side edges of the stock, a blade having an end portion extending transversely through the slot of the stock and formed with a longitudinally extending slot, the said end portion of the blade having a side extension projecting transversely therefrom with one edge forming a continuation of the end edge of the blade, there being calibrations along the blade adjacent the side edge thereof opposite its side extension and other calibrations across the adjacent end of the blade and a portion of the side extension, and an adjustable fastener passing through the slots of the stock and blade and adapted to releasably secure the blade in an angularly adjusted position.

In testimony whereof we affix our signatures.

WILLIAM H. EBERT. [L. S.]
ALBERT G. EBERT. [L. S.]
